United States Patent Office

Des. 223,709

Patented May 30, 1972

223,709

SNOWMOBILE SEAT

Yves Anselme Lapointe, Valcourt, Quebec, Canada, assignor to Bombardier Limited, Valcourt, Quebec, Canada

Filed Nov. 2, 1970, Ser. No. 25,769

Term of patent 14 years

Int. Cl. D12—16

U.S. Cl. D14—24

FIG. 1.

FIG. 2.

FIG. 3.

FIG. 4.

FIG. 1 is a perspective view showing one side, the upper portion and the front end of my design.

FIG. 2 is a perspective view showing one side of the seat and the rear and top parts of the back rest of my design.

FIG. 3 is a front elevation thereof.

FIG. 4 is a rear elevation thereof.

Each side of the seat is a mirror image of the other side.

I claim:

The ornamental design for a snowmobile seat, as shown and described.
